(57) **CLAIM**

The ornamental design for a sleeve for mobile devices, as shown and described.

DESCRIPTION

FIG. 1 is a perspective view of a sleeve for mobile devices embodying the new design;

FIG. 2 is another perspective view of the sleeve for mobile devices;

FIG. 3 is another perspective view of the sleeve for mobile devices;

FIG. 4 is a front view thereof;

FIG. 5 is a back view thereof;

FIG. 6 is a side view thereof;

FIG. 7 is another side view thereof;

FIG. 8 is a top view thereof;

FIG. 9 is a bottom view thereof;

FIG. 10 is a view of the sleeve for mobile devices in another configuration;

FIG. 11 is a view of the sleeve for mobile devices in another configuration;

FIG. 12 is a view of the sleeve for mobile devices in another configuration;

FIG. 13 is a view of the sleeve for mobile devices in another configuration;

FIG. 14 is a view of the sleeve for mobile devices in another configuration;

FIG. 15 is a view of the sleeve for mobile devices in another configuration;

FIG. 16 is a view of the sleeve for mobile devices in a state of use;

FIG. 17 is a view of the sleeve for mobile devices in another state of use;

FIG. 18 is a view of the sleeve for mobile devices in another state of use; and,

FIG. 19 is a view of the sleeve for mobile devices in another state of use.

In the drawings, the broken lines depict unclaimed subject matter only and form no part of the claimed design.
